UNITED STATES PATENT OFFICE

HARRY F. SHINDEL, OF READING, PENNSYLVANIA, ASSIGNOR TO WILLSON PRODUCTS, INC., OF READING, PENNSYLVANIA, A CORPORATION OF PENNSYLVANIA

DESIGN FOR AN ELBOW FITTING FOR RESPIRATORS

Application filed September 3, 1932. Serial No. 44,752. Term of patent 14 years.

To all whom it may concern:

Be it known that I, HARRY F. SHINDEL, a citizen of the United States, residing at Reading, in the county of Berks and State of Pennsylvania, have invented a new, original, and ornamental Design for an Elbow Fitting for Respirators, of which the following is a specification, reference being had to the accompanying drawing, forming part thereof.

Fig. 1 is a front elevation, and

Fig. 2 is a side elevation of an elbow fitting for respirators embodying my design.

What I claim is:

The ornamental design for an elbow fitting for respirators as shown.

In testimony whereof, I affix my signature.

HARRY F. SHINDEL.
